UNITED STATES PATENT OFFICE.

NATHAN C. JOHNSON, OF ENGLEWOOD, NEW JERSEY, ASSIGNOR TO CONCRETE APPLICATIONS COMPANY INC., OF NEW YORK, N. Y., A CORPORATION OF NEW YORK.

APPARATUS FOR GRADING AND QUANTITATIVELY DETERMINING COMMINUTED MATERIALS.

1,189,961.

Specification of Letters Patent.

Patented July 4, 1916.

Application filed May 5, 1915. Serial No. 26,147.

To all whom it may concern:

Be it known that I, NATHAN CLARKE JOHNSON, a resident of the city of Englewood, county of Bergen, State of New Jersey, have invented certain new and useful Improvements in Apparatus for Grading and Quantitatively Determining Comminuted Materials, of which the following is a description and specification.

10 My invention relates to new and useful apparatus whereby comminuted materials, such as sand, or crushed rock, or ores, or particles of comminuted material of any description, may be readily separated into 15 gradings of known size, such as would pass through, or be retained upon sieves of known, or standard openings in a more rapid and effective manner than would be obtainable in apparatus of a type other 20 than that herein described; and in addition to obtaining this rapid and effective separation and grading, this apparatus also renders possible the quantitative determination of the various separations, with maximum facility and minimum of error, where 25 such quantitative determination may be desired. It is not essential to the apparatus, or to the operation thereof, that devices for such quantitative determinations be attached 30 thereto, such uses being desirable in certain specific operations, though they may be applied to all, if desired.

One object of my invention is to facilitate the screening or grading, or separation 35 of comminuted materials such as ores or crushed rock, or sand, so that not only shall the screening, or separation be more effective, but also that it shall be accomplished more quickly and with less dependence upon 40 the personal skill of the operating individual than is usually the case.

Another object of my invention is to provide in simple, portable form an effective apparatus whereby the screening, or grading, or separation of comminuted materials of whatever kind or description may be rapidly and efficiently accomplished without dependence upon the skill of the operative for proper results.

50 Another object of my invention is to provide an apparatus in either portable, or non-portable form, whereby the grading, or screening, or separation of comminuted materials of whatever nature may be rapidly

and efficiently accomplished, regardless of 55 the moisture content of the comminuted materials, or of the relative proportions of one grade, or degree of comminution, to the other grades, or to the whole.

Another object of my invention is to provide an apparatus in either portable or 60 non-portable form, though preferably in portable form, whereby the screening, grading, or separation of comminuted materials, such as crushed rock, or sand, or such materials as may be used as the fine "aggregate" of concrete, may be quickly and efficiently accomplished, with the minimum of dependence upon the skill of the operator of 65 the apparatus, or upon the manipulation 70 thereof; and which shall, in addition to separating or grading the aforesaid comminuted material, provide means for determining the proportions of the several gradings of material with reference to the whole, 75 regardless of the exact volume or weight of the whole, within reasonable limits, or of the moisture content of the sample of comminuted material as chosen.

In carrying out the objects of my invention, as above described, I employ means 80 such as are illustrated in the five figures of the accompanying drawing.

In this drawing, Figure 1 shows a sectional elevation of the apparatus in position 85 for effecting the separation of the comminuted material. Fig. 2 shows a plan view of the same. Fig. 3 shows an elevation of the same, together with the attachments and appurtenances for determining the proportions of each grading of the material to the volume of the whole sample of material, such determinations being read directly in percentages if desired. Fig. 4 shows a section of Fig. 3, along the line X—X; and 90 Fig. 5 shows in detail the means employed to read in percentages of the whole the gradings and volumes of gradings of each size of the comminuted material, regardless 95 of the exact size or volume of the sample 100 chosen for the determination.

As will be seen from Fig. 1, the apparatus consists essentially of a tube, A, of appropriate diameter and length and of proper material, such as brass, carrying within it 105 by proper means a series of fabric screens, graded as to size in accordance with established usage in the arts, fixed at an angle to

the horizontal. The gradings of, or openings in these fabric screens vary in predetermined order from one end of the tube, A, to the other, these screens being denoted by the letter C in all figures of the drawing, wherein, in all cases, like letters refer to similar parts. The ends of the tube, A, are closed by removable ends, or plugs, B, forming substantially water-tight joints with the tube A. On one side of the tube A, are also attached funnel-shaped parts, D, mating their larger openings with like openings in the tube A, and carrying at their smaller ends glass tubes of proper size and length, E, these tubes having their major axes substantially parallel with the major axis of the tube A. These tubes, E, may, however have their major axes in any position desired or expedient, without departing in any way from the spirit of the invention, or without impairing its effective use. The location of the funnel-shaped parts, D, with reference to the fabric screens, C is such that the upper arc of contact between the inside-top of the tube A and the fabric screens C, is approximately co-incident with the larger openings of the funnel parts D and their mating openings in the tube A, as is seen in Fig. 1. These funnel parts, D and the glass tubes, E, are solely for the purpose of quantitative determinations of gradings and are not necessarily essential to the operations of separating and screening *per se*. For an understanding of the operation of these quantitative attachments, it will first of all be of service to describe the operations of separating, or screening by this apparatus. A sample of the comminuted material, made up, perhaps, of several different sizes, or gradings, or, it may be, composed only of one size of material, is introduced into the tube A by removing one of the end plugs, B. A quantity of water, not sufficient to fill the tube, A, is introduced with it. As before stated, the fabric screens, C are graded progressively from coarse to fine, in predetermined order, the coarser being at the end at which the sample is introduced. If, now, the tube A, in the position shown in Fig. 1, is rocked, or shaken, either by hand or by appropriate mechanical means, so that waves are induced in the water contained in the tube, the comminuted material will thereby be carried up on the sloping fabric screens in such manner that the finer materials will be quickly and thoroughly separated from the coarser with which they may be mixed, such separation being progressive on successive screen fabrics, in a manner more efficient and more rapid than obtains with screens not inclined.

In a portable apparatus, such as would be suited to the field examination of fine materials, or "aggregate" for use in con-

crete mixtures, the rocking, or shaking before described would be accomplished by holding the apparatus between the two hands of the operative. If then, after a few shakings, or rockings, sufficient for the grading and separation of the materials of different finenesses, the tube A being held during this operation in the position shown in Fig. 1, the tube A were reversed axially into the position of Fig. 3, it will be seen that the materials of each grade, as retained on each screen fabric, would be delivered by the reversed slope of the screen into the funnel-shaped pieces, D, through the registering openings in the tube, A. From the funnel pieces, D, it is evident that the materials would readily pass to the glass tubes, E, where the relative amounts of each could be read off by appropriate means, such, for instance, as that to be hereafter described in the following paragraphs.

It is a peculiarity of finely-divided, or of comminuted materials, such as crushed rock, or sand, that the volume occupied by a given dry weight will be different from the volume occupied by a like quantity of the same material which is not dry. It is further true that the volume occupied by any given quantity of such a material is dependent upon the quantity of water, or moisture contained in it. This phenomena is well-known and has been accurately determined for different kinds and gradings of material containing different percentages of moisture. It is also true that the quantity of moisture thus held by a comminuted material greatly affects its facility of separation, or grading, it being usually necessary to effect such grading subsequent to artificial drying, with consequent increased labor and expense. It follows from these statements that not only is there difficulty in grading the average comminuted material, because of its varying moisture content, with consequent variation in results, but further, for the same reason, it is essentially impossible to measure such grades volumetrically with sufficient accuracy to make such measurements, or determinations in any degree reliable. This introduces the necessity for drying, both for sifting and also for measuring. If, however, instead of drying so as to produce the uniform condition of absolute lack of moisture, the reverse condition of saturation is brought about, it is evident that comparisons on such basis will be always comparable, regardless of location or other variable factors which otherwise might affect the result. This condition of saturation, it is evident, is automatically brought about in this apparatus through the primary introduction of water in the tube A.

After the grading of the comminuted material, as before described, and its place-

ment in the several glass tubes, it is evident that the quantity of each material resulting from the screen separation can be gaged with fair accuracy by individual measurement of each tube; and the percentage of each determined by summation and division. This process, however, is too cumbersome for field determinations; and further it requires a degree of skill both in measurement and in computation which it is desired not to make necessary. But as the primary conditions of moisture of an undried sample necessarily cause its quantity to be variable, and to varying degrees according to its fineness, as before pointed out, such summation is essential to a correct determination. To this end, therefore and in order that it may be accomplished with as little demand as possible upon the skill of the operative, the mechanism detailed in Figs. 4 and 5 has been devised. It will be seen that this is mounted, in the portable apparatus shown in the drawing, upon a dovetailed bed attached lengthwise of the body tube A. Essentially, it consists of the dovetailed bed G, attached to the tube A, carrying the metal platen F, slidably mounted on the bed G, so that the platen F can by this means be moved from end to end of the tube A. Carried by this platen F, is a paper record-sheet, N, held to the platen F by appropriate means, as by clips. Also carried by the platen F are two indices, H and K, slidably mounted above the paper record-sheet, N on the platen F and adapted to pass along the sides of the glass tubes, E. It is evident, therefore, that after the separation of the material has been accomplished and the different grades of materials placed in their proper tubes, the quantity of the first grade can be marked on the paper index sheet, N, by sliding the platen F along the tube A to such position that the index K will register both with the zero of the index-sheet, N and with the bottom of the sand in the tube E. The second index, H, can then be slid along the platen F, until it registers with the top of the sand in the same tube. A pencil line drawn across it will indicate on the record-sheet the height of material in the first tube. It is evident, therefore, that if now the index K is moved along the platen to such position that it occupies the position formerly held by the index H; and if the platen is moved along the tube A until the index K registers with the bottom of the second tube, with repetition of causing the index H to register with the top of the second-grade material in this tube and a marking of this position on the record-sheet, N, that by this procedure, repeated a proper number of times, that on a comparatively small record sheet and without the requirement of skilled measurement, the total and

individual readings can be obtained by mechanical addition. This procedure, however, does not give the readings in percentages of the whole; and as before pointed out, the volume of the whole varies according to the moisture content of the sand, or other material chosen for examination and grading. If however, the record-sheet, N, is cross-ruled, as by printing in the preparation of the record-sheets for field service, so that a given length on one side represents a volume of 100% and a shorter length on the other side, say 20% shorter than the first length, also represents 100%, cross ruling through corresponding points on this record sheet will enable variations within the determined limits to be read directly from the pencil lines drawn across the indices H and K at their successive positions. To illustrate, in Fig. 5 is shown such ruling on a record sheet, the length at the left representing 100% and the shorter length at the right representing a like 100%, with cross rulings between these and intermediate points down to zero. In broken lines 1, 2, 3, &c., are represented the successive positions of the indices, H and K, with the manner of taking the last reading shown schematically. It is evident that if a vertical line is drawn through the intersection of the last line and the slanting 100% line, that the intersection of this vertical with the various readings can be read off directly in percentages by following the cross lines on the prepared record sheet. In this manner and by these means, the field examination of comminuted materials, such as sand, is taken out of the realm of skilled or delicate apparatus and manipulation and made possible with simple portable, efficient and accurate apparatus that can be used by a person of average intelligence.

What I therefore claim as my invention is:—

1. Apparatus for grading or separating comminuted or finely-divided materials into quantities of varying degrees of fineness, comprising a receptacle for the material to be treated having extending obliquely across it a plurality of approximately parallel screens of progressively decreasing fineness of aperture.

2. Apparatus for grading or separating comminuted or finely-divided materials into quantities of varying degrees of fineness, comprising a receptacle adapted for containing a mixture of comminuted material and liquid, said receptacle having extending obliquely across it a plurality of screens of progressively decreasing fineness of aperture.

3. An apparatus for grading or separating comminuted or finely-divided materials into quantities of varying degrees of fineness, comprising a tubular container closed

at one end and provided at its other end with a removable closure, whereby material may be introduced into the container, and a plurality of screens of progressively decreasing size of aperture extending obliquely across said container.

4. An apparatus for grading or separating comminuted or finely-divided materials into quantities of varying degrees of fineness, comprising a receptacle for the material to be treated having extending completely across it a plurality of partitions, each comprising a screen, these screens being of progressively decreasing fineness of aperture, and a plurality of branch containers leading from said receptacle at points intermediate the partitions thereon, such branch containers adapted for containing the material of the several grades into which the initial mixture is divided by the partitions.

5. An apparatus for grading or separating comminuted or finely-divided materials into quantities of varying degrees of fineness, comprising a receptacle for the material to be treated having extending across it a plurality of partitions, each comprising a screen, these screens being of progressively decreasing fineness of aperture, and a plurality of branch containers leading from said receptacle at points intermediate the partitions thereon, such branch containers adapted for containing the several quantities into which the initial mixture is divided by the screens and having transparent portions through which the quantities of the materials in such branch containers may be observed.

6. An apparatus for grading or separating comminuted or finely-divided materials into quantities of varying degrees of fine-

ness, comprising a receptacle for the material to be treated having extending across it a plurality of partitions, each comprising a screen, these screens being of progressively decreasing fineness of aperture, and a plurality of branch containers leading from said receptacle at points intermediate the screens therein, such branch containers adapted for containing the several quantities into which the initial mixture is divided by the screens, and means for quantitative determination of the various separations.

7. An apparatus for grading or separating comminuted or finely-divided materials into quantities of varying degrees of fineness, comprising a receptacle for the material to be treated adapted for containing a mixture of comminuted material and liquid, and having extending across it a plurality of screens of progressively decreasing fineness of aperture, and a plurality of branch containers each leading from said receptacle at a point approximating a corresponding screen.

8. An apparatus for grading or separating comminuted or finely-divided materials into quantities of varying degrees of fineness, comprising a receptacle for the material to be treated having extending across it a plurality of screens of progressively decreasing fineness of aperture, and a plurality of branch containers each leading from said receptacle at a point approximating a corresponding screen and each having a transparent portion substantially parallel with the axis of the main receptacle.
